CLAIM

The ornamental design for a chest compression apparatus as shown and described.

DESCRIPTION

FIG. 1 is a front, left, and top perspective view of a chest compression apparatus, with a strap of the chest compression apparatus shown in a closed state wherein a first part of the strap is attached to a second part of the strap; FIG. 2 is a front, right, and bottom perspective view of the chest compression apparatus, with the strap in the closed state;

FIG. 3 is a front elevational view of the chest compression apparatus, with the strap in the closed state;

FIG. 4 is a rear elevational view of the chest compression apparatus, with the strap in the closed state;

FIG. 5 is a left side elevational view of the chest compression apparatus, with the strap in the closed state;

FIG. 6 is a right side elevational view of the chest compression apparatus, with the strap in the closed state;

FIG. 7 is a top plan view of the chest compression apparatus, with the strap in the closed state;

FIG. 8 is a bottom plan view of the chest compression apparatus, with the strap in the closed state; and,

FIG. 9 is a front, left, and top perspective view of the chest compression apparatus with the strap in an open state in which the first part of the strap is detached from the second part of the strap.
